United States Patent Office

Des. 185,879
Patented Aug. 11, 1959

185,879

WASTE BASKET

Jean O. Reinecke, Oak Park, Ill., assignor to Federal Tool Corporation, Chicago, Ill., a corporation of Illinois

Application February 6, 1958, Serial No. 49,526

Term of patent 14 years

(Cl. D58—4)

FIG. 1

FIG. 2

FIG. 3

FIG. 4

Fig. 1 is a front elevational view of a waste basket embodying my new design;

Fig. 2 is a top plan view thereof;

Fig. 3 is a side elevational view of the waste basket; and

Fig. 4 is a bottom view thereof.

I claim:

The ornamental design for a waste basket, substantially as shown.
